UNITED STATES PATENT OFFICE

116,566

DESIGN FOR A TIE RACK

Ben B. Manaster, Chicago, Ill.

Application August 2, 1939, Serial No. 86,408

Term of patent 3½ years

To all whom it may concern:

Be it known that I, Ben B. Manaster, a citizen of the United States and a resident of Chicago, in the county of Cook and State of Illinois, have invented a new, original, and ornamental Design for a Tie Rack, of which the following is a specification, reference being had to the accompanying drawing, forming a part thereof, and in which:

Fig. 1 is a side elevational view of a tie rack in collapsed condition, showing my new design; and

Fig. 2 is a perspective view of the same in opened or extended condition, and as seen from the side opposite to that shown in Fig. 1.

I claim:

The ornamental design for a tie rack, as shown.
BEN B. MANASTER.
